UNITED STATES PATENT OFFICE

167,819

ELECTRIC BULB

Anna Yanks and Matthew Yanks,
Philadelphia, Pa.

Application May 16, 1952, Serial No. 19,732

Term of patent 3½ years

(Cl. D26—8)

To all whom it may concern:

Be it known that we, Anna Yanks and Matthew Yanks, citizens of the United States of America, residing at Philadelphia, State of Pennsylvania, have invented a new, original, and ornamental Design for an Electric Bulb, of which the following is a specification, reference being had to the accompanying drawings forming a part hereof:

Fig. 1 is a top plan view of an electric bulb showing our new design;

Fig. 2 is a side elevation of said electric bulb.

We claim:

The ornamental design for an electric bulb, as shown.

ANNA YANKS.
MATTHEW YANKS.
